UNITED STATES PATENT OFFICE

2,581,676

BOAT MOORING APPARATUS

William T. Loaney, Minneapolis, Minn.

Application August 11, 1948, Serial No. 43,726

3 Claims. (Cl. 114—230)

1

This invention relates to boat mooring devices. It is an object of my invention to provide a boat mooring device adapted to permit a boat to be securely moored out on the water by an operator standing on shore without necessitating the use of a separate boat to transport the operator to shore.

It is another object to provide a boat mooring device adapted to permit a boat to freely swing with the direction of the wind whereby the moored end of the boat will always be heading directly into the wind to permit the boat to ride extremely rough seas without shipping any water. My device also permits the boat to be transferred out to its mooring on the water by an operator standing on shore.

It is a further object to provide a boat mooring device easily adjustable for variations in water depth.

These and other objects and advantages of my invention will more fully appear from the following description made in connection with the accompanying drawings wherein like reference characters refer to the same or similar parts throughout the several views and in which;

Fig. 1 is a side view partially in elevation and partially in section showing my mooring device in operation with a boat secured thereto;

Fig. 2 is a fragmentary horizontal sectional view of the mooring post shown in Fig. 1 and taken substantially along the line 2—2 of Fig. 1;

Fig. 3 is a fragmentary side elevational view of the adjustable connection of the mounting post under water sheave as viewed substantially from 3—3 of Fig. 1; and,

Fig. 4 is a fragmentary elevational view of the underwater shore sheave as viewed substantially from 4—4 of Fig. 1.

As illustrated in the accompanying drawings, I provide a boat mooring device having a hollow adjustable mooring post 7 which is adapted to be securely anchored in upstanding relation in the bottom of the lake as by being telescopically received in a tubular member 8 driven into said lake bottom. The hollow mooring post 7, has a plurality of vertically spaced adjustment apertures 7a formed through the side walls thereof. The tubular anchor member 8 has cooperating apertures 8a formed through the upper portion thereof and a pin 9 is adapted to be removably received by an aperture 7a selectively aligned with an aperture of tubular member 8. The top extremity of hollow mooring post 7 is flared outwardly to form a fair-leader 7b for the mooring line of the boat. A plurality of windows 10 are

5 formed in spaced vertically aligned relation in the side of said hollow post 7 and a pair of opposed spaced sheave attachment flanges 11, best shown in Fig. 3, are mounted adjacent each of said windows and adapted to selectively attach a rotatable sheave 12 to said post 7 below the water surface. A pin 13 is removably inserted through opposed apertures formed in flanges 11 and journals sheave 12.

10 A second underwater sheave 14 is mounted on a dock post 15 in substantial alignment with sheave 12. A third sheave 16 is mounted at the upper portion of dock post 15 and suitable means such as the cleat 17 are provided for adjustably 15 securing a mooring line at the desired position.

An endless cable or line 18 is trained about sheaves 14, 16 and over the top fair-leader 7b at the top of hollow post 7 and down around sheave 12 disposed far enough below the water 20 surface to permit a boat 19 to freely swing thereabove. The boat 19 is securely attached to the line 18 as by a chain 20 and a hook 21 removably attaches said chain 20 to one end of the boat 19. From a practical standpoint it makes little 25 difference whether the boat is moored from the bow or the stern.

20 The following is the description of my improved boat mooring device. When an operator wants to moor his boat out on the water, he 30 merely lands at the dock and attaches the chain 20 to one end of the boat as by the hook 21. The line 18 is then pulled so that the lower run thereof travels inwardly and the upper run thereof travels outwardly drawing the boat 19 out 35 to the mooring post 7. The fair-leader will thus permit the chain 20 to freely swing around post 7 and the boat will thus be constantly headed into the wind to stably ride the waves. The line 18 is securely fixed in the desired position 40 as by cleating the same on the cleat 17. The upper run of the line 18 is raised and permits the boat 19 to swing around thereunder without interfering therewith and the lower run is submerged, as has been previously stated, and permits the boat to swing freely thereabove.

45 If the water level rises during the season, the sheave 12 may be raised as well as the hollow post 7. To raise the sheave 12, the pin 13 is merely removed from the flanges 11 and reinserted through the apertures in another selected 50 pair of flanges disposed thereabove. The post 7 may be raised by removing pin 9, raising the post and reinserting the pin 9 through another aperture 7a aligned with aperture 8a of the tubular anchor member 8.

It will be seen that I have provided a novel and highly efficient boat mooring device which is easily adjustable to various water levels and which will permit a boat securely moored thereto with complete freedom to swing about the mooring post 7 as a pivot so that said boat will always be headed directly into the wind to stably ride high waves. The device can be easily operated from a dock or from the shore and the boat may be drawing in or out from that position. These 10 devices are extremely easy and inexpensive to manufacture and can be widely used by resort proprietors and other boat owners.

It will, of course, be understood, that various changes may be made in the form, details, arrangement and proportions of the parts without departing from the scope of my invention.

What I claim is:

1. A boat mooring device comprising a hollow upstanding post adapted to be anchored substantially rigidly with the upper extremity thereof disposed a substantial distance above the water surface, an annular fair-leader fixed around the upper extremity of said hollow member, said member having a cutout side portion adapted to be disposed below the water surface when said post is in anchored position, and flexible line-guiding means mounted at said cutout portion, a flexible line trained over said fair-leader and extending downwardly within said hollow member to pass around said submerged guiding means and outwardly to form a lower run of said line submerged below the water surface and an upper run disposed in spaced relation above the water surface when said post is in anchored position, and means for attaching

5 one end of a boat to the upper run of said line, said attachment means being adapted to be drawn downwardly into said hollow member to permit the boat attached thereto to swing freely about said member.

2. The structure set forth in claim 1 and said submergible line-guiding means being vertically adjustable on said hollow member to permit the depth thereof to be controllably varied.

3. The structure set forth in claim 2 and means for controllably varying the height of said post.

WILLIAM T. LOANEY.
